Specification of Letters Patent. Patented Aug. 29, 1916.

Application filed September 1, 1915. Serial No. 48,475.

To all whom it may concern:

Be it known that I, JOSEPH KAUP, a citizen of the United States, residing at St. Louis, State of Missouri, have invented certain new and useful Improvements in Time-Clocks, of which the following is a full, clear, and exact description, reference being had to the accompanying drawings, forming a part hereof.

10 My invention has relation to improvements in time-clocks, and is more specifically directed to the signal actuating mechanism by which the workmen are notified when to begin or leave their work.

15 It consists in the novel features of construction more fully set forth in the specification and pointed out in the claims.

The object of the present invention is to provide a signal or an alarm actuating mechanism that will be automatically controlled by the time clock, which regulates the working hours of employees in large shops and plants. Further objects are to provide an alarm actuating mechanism that will be directly controlled by the arbor of one of the clock-hands; one that may be mounted inside the clock housing; one that is simple, yet positive in its action; and one possessing other advantages better apparent from 25 a detailed description of the invention with reference to the accompanying drawings, in which—

Figure 1 represents a front elevation of a clock, with parts broken away, showing my invention applied thereto; Fig. 2 is an enlarged top edge view of the actuating mechanism mounted between the clock-works frame and dial; Fig. 3 is a face view of my invention with the several parts in their respective positions when the signal or alarm is silent; Fig. 4 is a rear view of the invention with the respective parts in proper position during the sounding of the alarm; Fig. 5 is a vertical cross-section on the line 35 5—5 of Fig. 4; Fig. 6 is an enlarged elevational front detail of the spring contacts and links controlling the same showing the actuating mechanism just before its release from the tripper pins; Fig. 7 is a transverse section on the line 7—7 of Fig. 6; Fig. 8 is an enlarged detail similar to Fig. 6, the mechanism however being shown in its tripped position, and on its return or upward stroke. Fig. 9 is a transverse section on the 55 line 9—9 of Fig. 8; Fig. 10 is an enlarged

cross-sectional detail on the line 10—10 of Fig. 3; and Fig. 11 is an enlarged view showing in top plan the details of the lever which controls one part of the alarm circuit.

60

Referring to the drawing, C, represents a conventional clock-housing or casing for the clock-frame F and clock-works (not shown) as well understood in the art. Mounted in the frame F is the minute-hand arbor A, which is directly driven by the clock-works, said arbor having a drive pinion w mounted thereon adjacent the clock-frame F and the minute-hand H fixed to its outer end. The minute-hand arbor A has 65 the hollow hour-hand arbor or sleeve A' loosely mounted thereon at a point outside the frame F, said arbor A' carrying the hour-hand H' at its outer end. The arbor A' is driven from the pinion w meshing 70 with a gear wheel W on a counter-shaft n, said shaft being provided with a pinion w' which meshes with a gear wheel W' on the arbor A'. Secured to the frame F by means of brackets a or their equivalent is a bent 75 plate P, the same being interposed between the frame F and the dial D. At a convenient point the plate P is provided with a circular opening O which receives the hub s of a rotatable disk 1, which overlaps the 80 opening along one (front) face of the plate P, the end of the hub having secured thereto a disk 2 overlapping the opening along the opposite (rear) face of the plate, said disk 2 being provided with a central tubular 85 hub or bearing 2' for the arbor A' traversing the opening O' of the rotatable disk 1 and its hub s. The overlapping of the edges of the opening O by the members 1, 2, insures against displacement of the disk 1, 90 once its hub s is mounted in said opening. The disk 1 rotates in unison with the arbor A', being secured thereto by a clamp 3 which spans and grips the arbor, the free ends of the clamp being secured together by a screw 95 4 and nut 5, and the middle portion of the clamp being passed around or embracing a pin or stud 6 projecting from the outer face of the disk.

Secured to the disk 1 and projecting from 100 the face thereof near its periphery, are tripper pins p, p', p'', and p''', the first three of which are of equal length while the pin p''' is somewhat longer for a purpose to become apparent later. Mounted on the front of 110

the plate P is an oscillating lever 7, the short arm of which is adapted to be successively engaged and tripped by the pins p , p' , p'' , p''' , upon rotation of the disk 1, while the 5 long arm of said lever has connected to it a link 8 which is relatively movable longitudinally to a second link 9, said links being slidably connected by straps 10, 10, secured to the link 8, the link 9 passing loosely through 10 said straps. Bearing against the lower edge of the long arm of the lever 7 is the free end of a flexed spring 11 whose fixed end is secured by means of a clip h (or otherwise) to the plate P, said lever arm being limited 15 in its upward movement or oscillation by a stop or bracket 12 secured to the plate P. Projecting laterally from the upper portion of the plate P is an arm a' with a depending portion b' bent outwardly from the plane 20 of the plate. Pivotally connected to the member b' is one end of a lever 13, the link 9 being pivotally coupled to said lever at a point removed from the fulcrum thereof a distance equal substantially to one third the 25 length of the lever. The free end of the lever 13 has pivotally secured thereto the lower end of a vertically reciprocating rack-bar 14, the teeth t whereof mesh with the pins of a face-gear pinion 15 secured to, and 30 disposed about the axis of, a fly-wheel 16 mounted between the standards S, S', on the plate P, the standard S being formed integrally with said plate, the standards S' being secured to the base of the standard S. 35 The standards S' is provided with a laterally projecting guide 17 for receiving the rack-bar 14 and holding it in contact with the pinion 15 during the rack-bar's reciprocations. Mounted on a stud 18 secured to, 40 and projecting from the front of the plate P adjacent the disk 1, is a disk 19 provided with radially disposed arms 20, said disk being adapted to clear, and rotate in front of, the disk 1 which it slightly overlaps. 45 The object of the overlapping is to allow the pin p''' to engage the arms 20 for a purpose presently to be seen. The disk 19 may be provided with any suitable and appropriate number of arms (there being six in the present case). Projecting from the rear face of 50 the disk 19 are pins m , m , m , equally spaced apart (the number of pins being equal to half the number of arms on the disk 19) upon any one or two of which rests the free 55 end of a vertically oscillatable gravity lever 21 pivotally secured at one end to the plate P a suitable distance from the disk 19. Projecting from the lever 21 on the side opposite from the disk 19 is a stud 22 provided 60 with an outer sleeve 23 between which and the stud is interposed an insulating layer 24. Projecting upwardly from the plate P adjacent the standard S is an angle bracket 25 to which are secured socket-contacts 26, 26', 65 for receiving the wires 27, 27', the former

connecting with the battery B and the latter with the bell or other signal R, while that part of the circuit between the battery and the bell is made by the wire 28 (Fig. 1). The socket contacts 26, 26', are insulated from the bracket 25 (Fig. 2) to prevent short-circuiting through the plate P. Secured to the plate P on the opposite side from the bracket 25 is a holder 29 provided with sockets lined with insulating material 70 i , in which are respectively secured spring-arms or contacts 30, 30', the outer end of the arm or contact 30 being bent above the plane of the arm 30' (Fig. 4). The contact 30 at a point adjacent the holder 29 has 75 formed therein a slight depression d , to which is connected the bottom flattened extension e of the socket contact 26, said extension being bent at right angles to the socket 26 in order to meet the depressed portion d referred to (Figs. 2, 4). The contact 30' is provided at its free outer end with a Z-contact piece 31 for engaging the contact 30 when desired. Mounted on the same side of the plate P with the holder 29 and 80 slightly beneath said holder is a second socketed holder 32 in which are suitably mounted, and properly insulated the conductors 33, 33', the conductor 33 being suitably bent to couple with the flattened basal 85 extension e' of the socket contact 26', and the conductor 33' being suitably bent to connect with the contact 30'. Secured at one end to a hinge piece j and insulated therefrom, are a pair of conjointly oscillating 90 spring contacts 34, 34', the hinge member j and said contacts oscillating about a pin 35 projecting from the plate P on the side opposite that carrying the stop 12. The free ends of the conductors 33, 33', are in permanent rubbing contact at x and x' with the hinged terminals of the oscillating contacts 34, 34', respectively. Projecting from the link 8 is a pin 36 provided with an insulated sleeve v , a similar pin 36' projecting on the 100 same side from the link 9 and provided with an insulated sleeve v' , said pins being spaced apart to receive between them the resilient contacts 34, 34', which normally tend to spread apart and thus permanently bear 105 against the sleeves v , v' , carried by said pins. The distance between the pins 36, 36', is variable as we shall presently see, the maximum separation being reached when the terminal lug 9' of the sliding link 9 strikes 110 the adjacent strap 10 on the link 8.

The operation of the invention will now be described, and for convenience we will assume that the clock shown in Fig. 1 is for use in a business house or shop where the 115 working hours are from 8 o'clock a. m. to 12 o'clock noon, and from 12:30 o'clock p. m. to 4:30 o'clock p. m., thus making it necessary for the signal to be given the workmen at these hours. When the clock is running 120

the hour-hand arbor A' carries the disk 1 around with it in its rotation, the disk and the pins p, p', p'', p''' , consequently making one revolution every twelve hours. The pins p, p', p'', p''' , are so disposed on the disk 1 that they will successively engage and trip the short arm of the lever 7 upward before said pins can pass the lever, and the pins are so spaced around the disk as to release the lever 7, after having tripped it, at a predetermined time. Thus, in Fig. 1 the pin p''' is shown engaging the lever at 4:30 o'clock. Then, as the disk revolves (in a clockwise direction) the next pin p , which is spaced from the pin p''' a distance of three and one-half ($3\frac{1}{2}$) hours or seven twenty-fourths ($7/24$) of the circumference of the disk 1, will engage and trip said lever. The space between the pins p and p' (the pin p' engaging the lever at 12 o'clock) is four (4) hours or four-twelfths ($4/12$) of the circumference of the disk. The space between the pins p' and p'' represents the length of the lunch hour—a half hour in this case—or one twenty-fourth ($1/24$) of the circumference of the disk. The space between 12:30 and 4:30 o'clock (the end of the lunch hour and quitting time) is four (4) hours or four-twelfths ($4/12$) of the circumference of the disk. The spacing between the pins as above outlined merely serves as a single example, it being obvious that any other spacing may be improvised to suit conditions, and that the pins may be located with relation to any hours on the clock dial.

It is of course desirable that no signal be given during the night hours, or when the workmen are not expected at their appointed places of occupation, that is to say, the signals should be given during alternate twelve hours of the clock dial. The manner of restricting the signals to the twelve hours covering the period of work will be explained later on. The lever 7 upon being tripped by the pin p''' (Fig. 1) draws on the links 8, 9, which in turn oscillate the lever 13 through what may be termed as the drive-stroke, said lever 13 drawing the rack-bar 14 with it, thereby causing the pinion 15 and fly wheel 16 to be rotated in a clockwise direction. When the pin p''' releases the lever 7, the latter will assume its original position (Fig. 3) under the lifting influence of the spring 11, and be arrested in its movement by the stop 12. The movement of the lever 7 under the influence of the spring 11 may be termed the return stroke, and it will be observed that all the parts affected by the tension of the spring 11 will move in the opposite direction to that of the drive stroke. The fly wheel acts as a governor during this return stroke since much of the force exerted by the spring 11 is spent in rotating the fly wheel and thereby preventing a too rapid

return of the parts to their original position. By using a strong spring 11 the fly wheel can be rotated rapidly and if we use a comparatively weak spring the fly wheel can be caused to rotate slowly. 70

It will be observed by a reference to Fig. 6, that when the lever 7 draws on the link 8, said link will slide along link 9 until the lower strap 10, on the link 8, strikes the lug 9' terminating the link 9, at which time 75 both links will travel as a unit. Referring to Fig. 8, and assuming as shown by the arrow in said figure, that the lever 7 is moving upward or in the reverse direction from that indicated in Fig. 6, it follows that instead of the lever 7 pulling on the link 8 downward, it will push on said link upward, thus causing the link 8 and straps 10, 10, to slide upward along the link 9, the play between the links 8, 9, being availed 80 of by the lever 7 in its drive and return strokes as obvious from the drawings. The spring contacts 34, 34', bearing against their respective studs 36, 36', force these studs apart with their links 8 and 9 so that normally said contacts are held apart from each other. However, when the lever 7 is forced to make its return stroke (Fig. 8) under the influence of the spring 11, the force of the spring 11 is sufficient to overcome that of the contacts 34, 34', this causing the link 8 to slide over link 9, thereby shortening the space between the studs 36, 36', and bringing the contacts 34, 34', together which closes the circuit about to be traced. After 90 95 the pin p''' has engaged the lever 7 (for example at 4:30 o'clock) it continues in its revolution with the disk 1 and next encounters one of the arms 20 of the disk 19, causing said disk to rotate through an arc 100 of sixty (60) degrees or one-sixth of a complete rotation (there being six arms to the disk). The traverse of the disk 19 through the arc (60 degrees) referred to causes the gravity lever 21 to engage and rest on two 105 of the pins m, m , (which are three in number and disposed one-hundred and twenty degrees apart), the connecting line between which may be regarded as one side of an equilateral triangle, and which side the lever 21 may be said to span. Now, by referring to Figs. 1 and 4 it will be seen that the lever 21 is resting on but a single pin or on what may be considered as one of the vertices of the triangle above referred to, 110 that position of the lever being the highest assumed thereby, and the position of said lever when resting on two pins or along one of the sides of the triangle (Fig. 3) being the lowest assumed thereby. When the 115 lever 21 is in its lowest position, the contacts 30, 31, are allowed to spring apart, this condition remaining until the pin p''' has completed a full revolution (360 degrees) from the point of initial engage- 120 125 130

- ment with an arm (20) of the disk 19, when the disk will again be rotated or advanced angularly sixty degrees, and cause the presentation of a single pin m to the lever 21, thereby elevating the lever and forcing the stud 22 thereof against the bottom spring contact arm 30', and causing the contact terminal 31 thereof to engage the contact arm 30 (Fig. 4).
- 10 In Fig. 4 the pin p has just released the lever 7 which immediately starts on its return stroke during the initial portion or travel of which it forces together the contacts 34, 34', the pin p''' having previously rotated the disk 19 sufficiently to cause one of the pins m to engage and lift the lever 21 to cause the latter to lift the arm 30' and force the contact 31 against the contact 30. Under the conditions just described the electric circuit which we will now trace is closed, thus sounding an alarm and notifying the employees to begin work. This circuit is as follows: from the battery B, through the wire 27, socket contact 26, contact 30, contact 31, arm 30', conductor 33', rubbing contact at x' , spring contact 34', spring contact 34, rubbing contact x , conductor 33, contact 26', wire 27', bell R, wire 28, battery B (Figs. 1 and 4). The alarm or signal will continue to sound until the lever 7 strikes the stop or arresting bracket 12 (Fig. 3) when the link 8 coupled to said lever will be arrested in its upward movement. Thereupon the spring contact arm 34' engaging the pin 36' on the link 9 will lift said link sufficiently (or until the lug 9' strikes the lower strap 10) to cause a separation or break between the members 34, 34' the signal coming to a stop. Assuming that the signal referred to was the morning or eight o'clock signal, we see (Fig. 4) that the lever 21 is resting on a single pin m or on a vertex of the triangle whose sides connect the three pins m .
- 45 It was pointed out above that the pins p, p', p'' , were short, and the pin p''' long; and in this connection it may be stated that the lengths of the pins p, p', p'' , are insufficient to reach the arms 20 of the star-disk 19, the pin p''' being the only one of the series long enough to foul the arms of said disk. It follows therefore that the lever 21 (Fig. 3) will not be disturbed from its state of rest on the single pin m until the pin p''' has again engaged an arm 20 of the disk 19 and rotated the latter through an arc of 60 degrees. Obviously, successive engagements of the arms 20 by the pin p''' take place twelve hours apart; and assuming that the pin p''' trips an arm 20 say an hour before the pin p trips the lever 7 (and for convenience we will assume that the pin p trips the lever 7 at 8 o'clock in the morning and the pin p'' trips an arm 20 at 7 o'clock in the morning), it is obvious that the pin p''' will not again

trip an arm 20 until 7 o'clock in the evening or twelve hours later. But, when the next arm 20 of the disk 19 is so tripped, the latter will be again advanced through an arc of 60 degrees, thus causing a presentation to the lever 21 of two pins m (or one side of the triangle connecting the same) and allowing the lever to drop to lowest position and causing a separation between the contacts 30 and 31 (Fig. 3), so that when the lever 7 is subsequently (or at 8 o'clock at night) tripped by the pin p , no alarm can be sounded, because of the separation of the contacts 30, 31. This is as it should be as no signal at night is desired, all signals (under the present arrangement) being confined to the working hours between 8 a. m. and 4:30 p. m., as previously pointed out.

We have seen from the foregoing how the circuit was closed by the pin p tripping the lever 7 and subsequently releasing the same, and how the contacts 34, 34', were allowed to come together for closing said circuit, and how the circuit was broken by the arrest of the lever 7 against the stop 12 and the subsequent parting of the said contacts. This operation being now well understood, we need only to add that the same operations are repeated with the engagements of the pins p', p'' , and p''' with the lever 7 at 12 o'clock noon, 12:30 p. m. and 4:30 p. m. (or at any other times depending on the disposition and number of pins employed according to conditions to be met). It is of course within the purview of the skilled mechanic to provide a disk on the order of 19 or pins like p''' which will insure night signals if necessary.

It will be observed that the contacts 34, 34', are only in contact on the return stroke of the lever 7 so the signal will sound during the length of this stroke. The object of this is to allow the duration of the signal to be regulated by the spring 11; if a strong spring is used the time of the stroke (and signal) will be shortened, while if a weak spring is used the stroke will be slower and the signal longer. It would not be desirable to have the signal sound on the drive stroke, because this stroke is caused by the very slow movement of the hour-hand arbor and would result in a very prolonged signal. Therefore the sliding links 8, 9, are arranged as described in order that the contacts 34, 34', will be in contact only during the return stroke.

It is obvious that my device is susceptible of many modifications and changes in form of the various parts without departing from the spirit of the invention.

Having described my invention what I claim is:

1. In a signal actuating device, the combination with a clock provided with an arbor, of a disk mounted on said arbor and adapted to rotate therewith, suitable forma-

tions projecting from the face of said disk, a suitable electric signal, an electric circuit, means actuated by said formations for closing the circuit at one point, and a member 5 adjacent said disk operating to close said circuit at another point, and controlled by said formations.

2. In a signal actuating device, the combination with a clock provided with an 10 arbor, of a disk mounted on said arbor and adapted to rotate therewith, suitable formations projecting from the face of said disk, a source of electric energy, a suitable signal, an electric circuit interposed between said 15 source of energy and signal, means actuated by the formations on said disk for closing one part of said circuit, a rotatable member adjacent the disk adapted to be engaged by one of the formations on said disk for closing 20 another part of said circuit, the rotatable member coöperating with the means actuated by the formations on the disk to cause the signal to respond at predetermined intervals during every other revolution of the 25 disk, substantially as set forth.

3. In a signal actuating device, the combination with a clock provided with a rotatable arbor, of a disk mounted on said arbor and adapted to rotate therewith, suitable 30 formations projecting from the face of said disk, a source of electric energy, a signal device, an electric circuit interposed between said source of energy and signal device, a lever adapted to be oscillated by 35 the formations on aforesaid disk, and governor-controlled means coöperating with said lever for closing the electric circuit upon an oscillation of the lever in one direction whereby said signal is made responsive.

4. In a signal actuating device, the combination with a clock provided with a rotatable arbor, of a disk mounted on said arbor and adapted to rotate therewith, suitable 45 formations projecting from said disk, a source of electric energy, an alarm sounding device, an electric circuit interposed between said source of electric energy and said device, a lever having short and long arms 50 mounted adjacent the disk and adapted to be engaged by the formations on said disk, links connected to the long lever arm of said lever and relatively slidable on each other, a rotatable member contiguous to the disk 55 and adapted to be engaged by one of the formations on said disk, the aforesaid links operating to close one part of the circuit upon oscillation of the lever in one direction, and the rotatable member operating to 60 close another part of said circuit at prede-

termined intervals, thereby causing the alarm to sound, substantially as set forth.

5. In a signal actuating device, the combination with a clock provided with a rotatable arbor, of a disk mounted on said arbor 65 and adapted to rotate therewith, suitable formations projecting from said disk, a source of electric energy, an alarm sounding device, an electric circuit interposed between said source of energy and sounding 70 device, a lever adapted to be oscillated by the formations on said disk, means coöperating with said lever for closing the electric circuit upon an oscillation of the lever in one direction, and means for maintaining 75 said circuit closed for a certain period of time, whereby a sustained alarm is sounded.

6. In a device of the character described, an oscillating lever pivoted at an intermediate point of its length, clock-controlled 80 means for actuating said lever, a link coupled pivotally to one arm thereof, a second link mounted slidably along the first link, a lever pivoted at one end and pivotally coupled at an intermediate point to 85 the adjacent end of the second mentioned link, a rack-bar pivotally coupled to the free end of the second lever, a pinion engaging said rack-bar, pins on the links spaced apart, a pair of oscillating spring 90 arms or contacts engaging contiguous faces of the pins, a spring for actuating the first mentioned lever and links in one direction, and a stop for arresting the lever and permitting independent control of one of the 95 links by the spring arm engaging the pin thereof.

7. In a device of the character described, a chronometrically rotated disk, a series of pins projecting from one face thereof, one 100 of the pins being longer than the remaining pins of the series, an electric circuit, a pair of normally separated spring contact arms, a lever actuated by the pins, means interposed between the lever and contacts for 105 closing said contacts with a movement of the lever in one direction, a rotatable star-disk periodically advanced by the long pin of the series, a pair of spring contact arms normally spaced apart, and means interposed between said star-disk and last mentioned contact arms for forcing the contacts together at predetermined rotations of the star-disk.

In testimony whereof I affix my signature 115 in presence of two witnesses.

JOSEPH KAUP.
